FIG. 1 is a top plan view of a brassiere showing my new design; and

FIG. 2 is a bottom plan view thereof.

The characteristic features of my design reside in the combination on the brassiere disclosed of the scalloping on the upper inner half of each cup, a floral pattern parallel to the scalloping, the material above the scalloping being of plain net, together with a matching net insert between the cups which insert is similarly scalloped at its lower end as well as an embroidered flower at the notch, all as shown.

I claim:

The ornamental design for a brassiere, as shown and described.
